(57) **CLAIM**

The ornamental design for a combined magnetic hanger and tilt stand for a portable test tool, as shown and described.

DESCRIPTION

FIG. 1 is a top plan view of a combined magnetic hanger and tilt stand for a portable test tool showing my new design. FIG. 2 is a bottom plan view thereof.

FIG. 3 is a left side elevation view thereof.

FIG. 4 is a right side elevation view thereof.

FIG. 5 is an inverted front elevation view thereof.

FIG. 6 is a rear elevation view thereof.

FIG. 7 is a bottom left perspective view thereof.

FIG. 8 is a top plan view of a combined magnetic hanger and tilt stand for a portable test tool positioned for hanging a portable test tool.

FIG. 9 is a right side elevation view thereof, positioned as shown in FIG. 8; and,

FIG. 10 is a perspective view of the combined magnetic hanger and tilt stand for a portable test tool positioned to provide a tilt stand for a portable test tool.

The broken line showing of a device in FIGS. 8-10 illustrates environment of the claim. The remainder of the broken lines depict portions of the combined magnetic hanger and tilt stand for a portable test tool. The broken lines in the figures form no part of the claimed design.
